FIRING MECHANISM FOR LINE
THROWING GUNS

Arthur Hubalek, Brooklyn, N. Y.

Application June 3, 1944, Serial No. 538,611

1 Claim. (Cl. 89—27)

The invention disclosed herein relates to mechanism for firing guns such as used for throwing lines between ships or between ships and shore.

Special objects of the invention are to provide mechanism for firing guns of the type mentioned, which can be quickly mounted on or removed from the gun barrel, which will consist of but few parts and those of simple rugged design, not subject to breakage or getting out of order, which will be easy to load and unload, positive in action and, while easy to fire by lanyard pull or the like, safe up to the moment of actual firing.

Other desirable objects and the novel features of the invention by which the intended purposes are attained are set forth or will appear in the course of the following specification.

The drawing accompanying and forming part of the specification illustrates a present practical embodiment of the invention, but it will be appreciated that structure may be modified and changed in various ways, all within the true intent and broad scope of the invention as herein-after defined and claimed.

Fig. 1 in the drawing is a side elevation of a line throwing gun having the invention incorporated therein.

Fig. 2 is an enlarged longitudinal sectional view across the breech of the gun, as on line 2—2 of Fig. 1.

In the illustration, 7 designates the barrel of a muzzle loading cannon such as the invention is usually applied to. Over the breech portion, this barrel is provided with a coarse screw-threaded passage 8, to receive the correspondingly screw-threaded stem 9, of the breech piece 10.

The latter is shown as having an angular head 11, by which it may be turned down firmly over a concaved washer 12, seated over the top of the barrel.

Above the head, the breech piece is shown as having a screw-threaded portion 13, of slightly larger diameter and finer screw pitch than the mounting shank portion 9.

Extending entirely through the breech plug is a bore 14, which may be of the same diameter throughout, but which at the upper end at least is of a size to form a chamber for a blank cartridge 15, such for example, as 32 caliber or the like.

The cartridge chamber is shown as having a narrow raised rim 16, providing a seat for the flange or rim of the cartridge and the top of the breech piece is shown as concaved upwardly to this cartridge seat to facilitate easy removal of an exploded cartridge.

The cartridge chamber is closed over by a removable breech head 17, internally screw-threaded at 18, to fit the screw-threaded portion 13, and externally shaped at 19, to take a wrench or the like.

This removable breech head has a concentric cylindrical tubular extension 20, in which the firing pin 21, is slidably guided and over which the hammer 22, is slidably guided.

10 The point of the firing pin operates through a hole 23, provided in the breech head and back of this point, the pin is enlarged or flanged at 24, to provide a step or shoulder for the spring 25, surrounding the stem of the pin and bearing against the screw plug 26, closing the outer end of the tubular extension 20.

15 The stem or shank portion of the firing pin slides freely through the spring abutment plug 26, and is attached to the hammer by a cross pin 27.

20 The hammer and connected firing pin are held in cocked position by a trigger in the form of a yoke 28, arched to fit over the hammer head 22, and pivoted to the latter by means of the cross pin 27, securing the hammer and firing pin together.

25 The ends of this yoke are shown as squared off to rest flat on an annular shoulder or step 29, about the base of the firing pin guide extension 30 20, and the relation of the parts is such that when the trigger yoke is lined up in engagement with such shoulder, it will hold the hammer and firing pin retracted in cocked relation.

30 For tripping the trigger, a bail or ring 30, is shown pivotally connected with the spaced arms of the trigger yoke, to which a lanyard 31, or the like, may be connected.

A safety lock is provided in the illustration, in the form of a spring cotter pin 32, insertable 40 through openings 33, 34, in the outer arched end of the trigger yoke and hammerhead respectively, when the parts are in fully cocked position and connected with the lanyard ring by a short chain 35.

45 The hammerhead 22, is shown as of generally rectangular cross-section, with flat parallel sides, over which the trigger yoke may freely pivot.

The abrupt inner ends of the trigger yoke by their extended engagement with the supporting shoulder 29, maintain the trigger firmly in cocked relation and keep it safe against any accidental or unintentional release. At the same time however, only a slight but firm pull on the lanyard is necessary to effect the release.

55 To avoid any chance of the trigger yoke catch-

ing or failing to release the hammer and firing pin, the breech head is shown as relieved in a concave flare 36, immediately below and about the annular sear or supporting shoulder 29. This structure makes certain that the ends of the yoke 5 will swing free and clear of any contact as they leave the sear or supporting surface 29.

The entire mechanism is relatively small and the parts are compactly disposed, so as to take up but small space and project only a slight distance above the gun barrel.

The mechanism is readily applicable to any ordinary cannon by simply screw-threading the touch-hole to take the threaded stem of the base or breech piece. The parts preferably are made of stainless steel or the like, so that they will always remain in proper working condition in all kinds of weather and without requiring particular care or attention.

The head carrying the firing pin and trigger mechanism is quickly attachable to and removable from the fixed breech piece, enabling quick and easy loading and ejection of the cartridges. The firing mechanism carried by the removable head may be cocked before or after applying it to the breech piece carrying the cartridge. Hence the firing mechanism may be cocked and set at safety before screwing it into position over the cartridge and it may then be left on safety, right up to the moment it is to be fired. The change from safety to firing condition is immediately accomplished by simply pulling out the spring cotter pin, leaving it hung on to the lanyard ring, ready for instant use.

The spring pressed firing pin and hammer unit, carrying the trigger yoke, are rotatably mounted in and on the tubular stem of the breech head, enabling these parts to be turned for pull of the lanyard in any desired direction.

The shoulder 29, for holding the parts in cocked relation is shown as a relatively narrow

ledge to avoid undue friction between this shoulder and the ends of the trigger yoke or lever. By connecting the lanyard with the inner ends of the yoke, the trigger releasing force is applied close to the stationary supporting part of the mechanism and without introducing any tendencies to cause the parts to bind, through changing leverages, or the like. The supporting stem forming the base or cartridge holder portion of the mechanism may be made up in one piece. Likewise, the breech head which forms the cap or cover over the cartridge holder can be made up in one piece. The trigger yoke which in service acts in the capacity of a pivoted toggle lever, can be made up from a single strip doubled upon itself in the form of an arch or loop having substantially parallel sides.

The cotter pin 32, may be fashioned with a chisel-pointed end or the like, to provide immediately available means for effecting extraction of the exploded cartridge.

What is claimed is:

Gun firing mechanism comprising a tubular cartridge holder, a breech head having a readily removable screw threaded engagement on said cartridge holder, a firing pin longitudinally slideable through said breech head, a hammer head on the outer end of said firing pin spring for driving said firing pin toward the end of the cartridge holder, a yoke arched about said hammer head and firing pin and having substantially parallel side portions at opposite sides of and pivotally connected with said hammer head and firing pin, a supporting shoulder disposed for engagement by the ends of said opposite sides of said pivoted yoke and disposed when so engaged to enable the yoke to hold the firing pin in retracted position, and means for tripping the ends of said pivoted yoke from supported engagement 35 with said shoulder.
